UNITED STATES PATENT OFFICE.

LOYD I. ALDRICH, OF PONTIAC, ILLINOIS, ASSIGNOR TO JOHN ROCKE, OF PONTIAC, ILLINOIS.

DRIVING MECHANISM FOR WASHING-MACHINES.

1,185,573.

Specification of Letters Patent. Patented May 30, 1916.

Application filed July 6, 1915. Serial No. 38,108.

To all whom it may concern:

Be it known that I, LOYD I. ALDRICH, a citizen of the United States, residing at Pontiac, in the county of Livingston and State of Illinois, have invented certain new and useful Improvements in Driving Mechanism for Washing-Machines, of which the following is a specification.

My invention relates to washing machines, and more particularly to driving connections for a clothes agitator as for instance, a dolly of the common type.

My invention has, special reference to mechanism and parts looking to the points of simplicity, cheapness and efficiency, and to this end I have developed a gear drive connection that is permanent, durable and easy running and is effectually safeguarded against accident and breakage.

My invention consists in combining or connecting a driving and a driven element in a relation to promote disconnection therebetween at the will of the operator; in providing separable clutch elements yielding relatively that the jar of establishing connection may not damage or injure the parts or gear driving connection; in providing a driving connection at the top of the washing machine that shall present the least possible projection or extension above said top to the end that the top may be utilized as a rest for containers that may be placed thereon.

My invention also includes a special form of gear parts and supports for the same.

Other detail matters relating to my invention will be hereinafter more particularly pointed out.

In the drawings,—Figure 1 is a top plan view of my invention; Fig. 2 is a side elevation of the same; Fig. 3 is a bottom view of my invention; Fig. 4 is a detail view in elevation of gear drive connections including separable clutch parts, and Fig. 5 is a view, partially in section, including in illustration gear driving parts and the manner of supporting the same.

Referring to the above figures, 2 is a tub or container for clothes; 3 are supporting legs for the tub; 4 and 5 are permanent sections of a top covering or lid for the same. 6 is also a portion of the lid, the same being hinged as at 7 to the permanent lid portion 6 and 8 is a common interlock device serving to lock the lid 6 in a closed position.

9 is a dolly of the well known type, the same being permanently connected to the lower end of squared shaft 10, said shaft being carried in a sleeve extension 11 from a sprocket gear member 12. A cap 13 is fixed to the upper end of squared shaft 10, serving as a stop to limit its downward movement, said cap abutting and being supported normally upon the top or hub portion 14 of sprocket gear 12. The sleeve portion 11 of gear 12 is housed or journaled in the sleeve portion 15 of plate 16. The outer walls of the upper end of sleeve 15 are inclined as shown, and serve as a seat or support for gear 12, said gear being provided with an annular groove 17 conforming in shape to the inclined wall of said sleeve 15, whereby the supporting surface bearing between said gear and its support is extended to the largest limits possible for the purpose of distributing the wear therebetween. The sleeve extension 11 of gear 12 is provided, and its inclosure within the walled bearing or sleeve 15 of plate 16, for the purpose of reinforcing and strengthening the support for shaft 10, and similarly, for insuring the maintenance of gear 12 in a permanent position. The plate 16, together with the gear and driving connections just above described, are mounted on the movable lid portion 6. 85 Plate 16 extends outwardly beyond the limits of movable cover portions 6, between which a shaft 19 depends, the latter being carried within the sleeve 20 and supported therein by means of collar 21 fixed to said shaft. Sleeve 20 is provided with lugs 22 that are secured to lugs 18 by means of bolts 23. A sprocket wheel 24 is fixed to shaft 19 and sprocket chain 25 serves to establish a driving connection between said sprocket 95 wheel 24 and sprocket wheel 12. 26 is a clutch member secured to the lower end of shaft 19.

The parts above described comprehend the agitator element for a washing machine and driving connections therefor, and all these parts are designed to be supported upon the movable lid portion 6 and to swing with the movement of said lid. Beneath the washing tub I have provided a framing support comprising angle bars 27 and transverse bar 28. This frame is designed to support gear parts of the machine.

The operating elements of the machine derive initial power commonly from a motor 110

- or gasoline engine (not shown) transmitted through belt wheel 29 to shaft 30, the latter supported in sleeve portion of bracket 31 which is connected with the framing beneath the tub.
- 5 32 is a bevel gear fixed to shaft 30.
- 33 is a bevel gear fixed to shaft 34, the latter being suitably supported in connection with framing member 28.
- 10 35 is a crank arm fixed to shaft 34.
- 36 is a crank arm fixed to vertical shaft 37, said crank arms being connected by means of link 38. Shaft 37 is carried in bearing 38 in bracket member 39, the latter being fixed to one of the framing members 27, and similarly within a vertical standard 40.
- 15 41 is a clutch member designed at times to engage with clutch member 26 on shaft 19, said clutch member 41 being splined upon shaft 37 and held for normal clutch relation with said clutch member 26 under tension of spring member 42, the latter having a bearing relation between the hub portion of clutch member 41 and the upper end of standard 40. This sliding connection of clutch 41 upon shaft 37, under the tension of spring 42, will permit clutch member 41 to yield and to be disposed under abnormal conditions, that is, in case when the lid or 20 cover 6 is being closed, the outer end of the tooth members of the clutch come into contact. This character of connection prevents severe jar or damage to the clutch members and connected gear parts generally. About 25 normal contact of the clutch members will be remedied, as shaft 37 is turned, as with such turning the teeth of the clutches will be brought into normal driving engagement.
- In operation, the parts being arranged in 30 the manner shown in the drawing, with the lid or cover portion 6 closed, a driving connection will be established from the power source to the agitator or dolly, and in course dolly shaft 10 will be reciprocated reversely alternately to cause the dolly to be turned back and forth. When the lid or cover 6 is raised, clutch parts 26 and 41 will be separated and the agitator or dolly will cease to operate and the connected driving parts that are mounted upon the lid, while the other driving connections will continue to run. In this manner, a very simple, durable and safe 45 intermittent driving connection is provided for the agitator.
- 50 55 What I claim is:
1. In a device of the class described, a main frame including supporting member, driving mechanism thereon including a vertically disposed turnable member, a support for said member, a clutch member, its engageable face disposed at right angles with the axis of said member and capable of adjustment lengthwise thereof, a movable member on the supporting member provided with operating mechanism thereon, and

movable therewith, including a clutch connected to operate said operating mechanism and disposed to register with the clutch on the turnable member when the closure member is in closed position and to be separated therefrom when said closure member is raised.

2. In a device of the class described, the combination of an upright driving shaft, a sleeved member about the same spaced from the upper end of said shaft, a support movable relatively to said upright shaft, operating mechanism on the movable support, a power transmission element on the upper end of the upright driving shaft movable lengthwise of said shaft, a resilient member interposed between said power transmission element and the upper end of said sleeve, and a power transmission element connected with said operating mechanism, and arranged to be engaged when the support is in the normal operating position and disengaged therefrom when the support is moved from the operating position.

3. In a device of the class described, the combination of a main frame, power driving mechanism under the main frame, an upright shaft connected to be oscillated from the driving mechanism, a standard for housing said upright shaft terminating short of the upper end of the latter, a power transmission element upon the upper end of said upright shaft movable lengthwise thereof, a resilient member interposed between said power transmission element and the upper end of said standard, a support movable relative to the main frame, operating mechanism on the movable support, including a power transmission element, said power transmission elements being arranged to be interengaged when the movable support is in normal operating position and adapted to be disengaged when the support is moved from said position.

4. In a device of the class described, the combination of a driven member having a reversing movement, a housing standard for said driven member terminating short of the upper end of the latter, a support movable relatively to said member, an operating mechanism on the support, separable clutch parts connecting said member and the operating mechanism, one of said parts being slidably lengthwise of said member and a resilient member interposed between said clutch part and the upper end of the standard, said clutch parts being arranged to be engaged when the support is in the operating position and to be disengaged when the support is moved therefrom.

5. In a device of the class described, the combination of a main support, a drive shaft thereon, a support movable relative to said drive shaft, a housing member for said drive shaft terminating short of its upper

end, an operating mechanism on the movable support, an operating shaft connected with the operating mechanism, said operating shaft being arranged in alignment with the 5 drive shaft, separable power transmission members one upon each and intermediate of said shafts, the member on the drive shaft being movable lengthwise thereof, and a resilient member interposed between the 10 power transmission member on the drive shaft and the upper end of the standard, said members being arranged to be in engagement when the support is in operating position and adapted to be disengaged when 15 the support is moved from said operating position.

6. In a driving mechanism for washing machines, the combination with a main support and a movable support coöperating therewith, of a vertically disposed actuating shaft mounted on said main support, a housing standard for said actuating shaft terminating short of its upper end, an operating member mounted on said movable support in alignment with said actuating shaft, a driven shaft also mounted on said movable support, connecting means between said driven shaft and said operating member, coöperating clutch members, one upon said 25 actuating shaft and the other on the operating member, the clutch member on the actuating shaft slidable lengthwise thereof and a resilient member interposed between the clutch member on the actuating shaft 30 and the upper end of the housing standard.

7. In a driving mechanism for washing machines, the combination with a main support and a movable support coöperating therewith, of a vertically disposed actuating shaft mounted on said main support, a housing standard for said actuating shaft terminating short of its upper end, means for oscillating said actuating shaft, an operating member mounted on said movable 40 support, a driven shaft also mounted on said movable support, connecting means between said driven shaft and said operating member, coöperating clutch members one upon said actuating shaft and the other on said 45 operating member, the clutch member on the actuating shaft slidable lengthwise thereof and a resilient member interposed between the clutch member on the actuating shaft and the upper end of the housing standard.

55. 8. In a driving mechanism for washing machines, the combination with a main support and a movable support hinged thereto, of an actuating shaft mounted on said main support, a housing standard for said actuating shaft terminating short of its upper end, a clutch member slidably connected with the upper end of said actuating shaft,

a resilient member interposed between said clutch member and the upper end of the housing standard, a vertically driven movable shaft mounted on said movable support, a gear member carried on said driven shaft provided with an elongated sleeve portion, and an annular recess in its lower face, a cast member on the movable support provided with an elongated sleeve portion inclosing the sleeve portion of the gear member, its upper end extending above the said cast member and formed to conform with the angular formation of the annular groove 75 in the gear member, a short driven shaft mounted at the outer end of the cast member of the movable support, a gear member thereon, driving connections between said gear member on the short driven shaft and 80 the gear member upon the driven shaft, and a clutch member on the short driven shaft for coöperation with the slideable clutch member on the upper end of the actuating shaft.

85. 9. In a device of the class described, a main frame including a supporting member, driving mechanism therefor including a turnable member, supporting means for said turnable member, a clutch member connected to said turnable member, a movable member on the supporting member and provided with operating mechanism thereon and movable therewith, said operating mechanism including a clutch member movable into 90 engagement with the clutch member on the turnable member by movement of the movable member to normal operating position and disengaged from the clutch member of the turnable member upon movement of the 95 movable member from normal position.

10. In a device of the class described, a main frame, a driven shaft supported by said main frame, a movable support on the main frame, a driven shaft, a cast member 105 carried by the movable support and supporting at one end the driven shaft, an operating shaft, an elongated sleeve at the other end of the cast member and inclosing the operating shaft, a gear member on the 110 operating shaft provided with a sleeve portion inclosed by the elongated sleeve of the cast member said elongated sleeve serving as a support for said gear member, and driving connections between the driven shaft 115 and the gear member on the operating shaft.

In testimony whereof I have affixed my signature in presence of two witnesses.

LOYD I. ALDRICH.
